INVENTOR.

Charles B. Locke

UNITED STATES PATENT OFFICE.

CHARLES B. LOCKE, OF APPONAUG, RHODE ISLAND.

BEER-FAUCET.

SPECIFICATION forming part of Letters Patent No. 352,140, dated November 9, 1886.

Application filed January 9, 1886. Serial No. 188,075. (No model.)

To all whom it may concern:

Be it known that I, CHARLES B. LOCKE, of Apponaug, in the county of Kent and State of Rhode Island, have invented certain new and useful Improvements in Beer-Faucets; and I do hereby declare that the following is a full, clear, and exact description thereof, reference being had to the accompanying drawings, and to the letters of reference, marked thereon, which form a part of this specification.

The object of this invention is to construct a faucet that can be applied to a barrel containing beer under pressure without allowing any of its contents to escape, and that at the same time shall avoid the complex structure and valves found in faucets made for that purpose, and consequently be less expensive. It is fully illustrated in the accompanying drawings, in which—

Figure 1 shows a side elevation of the faucet, with a part of a barrel-head in section. Fig. 2 is a side view of the plunger that slides inside of the faucet. Fig. 3 shows a modification of the faucet. Fig. 4 shows the tube that goes in the barrel-head, (see *a* in Figs. 1, 3, and 7.) Fig. 5 is a part of a barrel-head, showing a cover for the tap-hole. Fig. 6 shows a section of a part of a barrel-head with the tap-hole and plug *d*, without the tube *a*. Fig. 7 is a vertical section lengthwise of the faucet shown in Fig. 1 attached to a barrel, a part of the plunger being shown in elevation.

The faucet consists of a body, *B*, made preferably in an octagon shape in cross-section, and having a straight hole through its center lengthwise. The end of the faucet that is to be attached to the barrel has its center bore enlarged for a short distance in, and a screw-thread made in this enlarged portion. The outside of this same end has a tapering screw-thread, *c*, made on it after the manner of faucets intended to screw into the wooden head of a barrel, and a collar is put at the inner end of the threaded portion to form a bearing against the barrel-head *C*. The other end of the body *B* is turned down and a screw-thread made on it to screw into the cap *D*, which has a similar screw-thread made in it. A hole is made through the cap *D* concentric with the bore of the body *B*, but of a smaller diameter, and a ring of suitable packing is placed between the end of *B* and the inside of the cap *D*. A pro-

jecting hook, *e*, is attached to the outside of the cap *D*, to receive a projection, *e'*, made on the head of the plunger *A*. A projection, *h*, is made on one side of the faucet at about midway of its length, through which there is a hole opening into the main bore of the faucet. A screw-thread is made on the outside of the projection *h*, upon which is screwed the collar *i*, onto which the lead pipe is soldered that connects the faucet with a fountain.

A round bar or plunger, *A*, Fig. 2, is made to go in the center of the faucet. That part of it from the shoulder at the packing *b* to the end at the left is made of a size to just slide freely in the bore of the faucet; but that part between the shoulder and the head is made smaller, so as to just pass easily through the hole in the cap *D*. A packing, *b*, is wound around the plunger *A* in a groove made to receive it, the object of the packing being to make the plunger fit tightly in the bore and prevent the liquor from passing.

The outer end of the plunger *A* has a head attached with a short cross-bar in it, by which it is moved when necessary. A ring of packing, *f*, is placed in the end of the faucet.

a is a short tube just long enough to reach through the barrel-head, with a hole through it of the same size as the bore of the faucet. One part of the tube *a* is left plain to drive into the head of the barrel, while the other part has a screw-thread, *s*, made on it to fit into the chambered end of the faucet.

The tube *a* is put in the head of the barrel in the following manner: A hole is made of such size that the tube will drive tight in it. The outer part of the hole is then counterbored large enough for the whole end of the faucet up to the collar. The tube *a* is driven into the hole until the screw end is just flush with the outside of the head. *d* is a plug of wood put into the tube *a* when the barrel is filled. Fig. 6 shows how the plug *d* is held when no tube is used.

When the faucet is to be inserted into the barrel, the plunger *A* is drawn out, as shown in Fig. 1. The faucet is then screwed onto the tube *a* until the end of the tube presses against the packing *f* in the faucet. The plunger *A* is then driven in far enough to force the plug *d* into the barrel, and drawn back until the shoulder above the packing *b* rests against

the inside of the cap D, (see dotted lines in Fig. 7,) when there will be a free passage for the beer from the barrel to the pipe on the projection h. It will be readily seen that no beer can pass the packing b during this operation whatever the pressure may be in the barrel. When it is necessary to cut off the flow to the fountain, the plunger A is turned a little to one side and pushed clear in, and then turned so that the projection e' on its head will be under the catch e on the cap D, which will hold the plunger in against the pressure in the barrel, and no beer can pass out because of the packing b. The operation is the same in applying the faucet to a barrel in which the ordinary faucet screwing into the wood has been used, (see Fig. 6,) excepting that the outside thread, e, is screwed into the wood. The objection to this latter mode of holding the faucet in is, that the thread g in the wood becomes worn and will not hold the faucet in. The modification shown in Fig. 3 is to enable one to draw beer at the outer end of the plunger, for which purpose it is made hollow, and has a screw-cap, r, put on its outer end, to be removed when it is desired to draw from that end.

The cap s' (shown on the barrel-head C in Fig. 5) is for the purpose of closing the tap-hole when the barrel has been emptied, and preventing it from becoming sour or moldy inside. The "collar" may be left off, as it is not essential in using the faucet.

This faucet has the advantage of being easily made at a small cost, and it has no ground valves to become leaky and require regrounding. The packing b—the only part liable to wear—can be easily renewed by any one.

Having described my improvements, what I claim as my invention is—

In a beer-faucet, the combination, with the hollow body B, having an outlet near its center and an exteriorly and interiorly threaded inner end, of the tube a, threaded for a portion of its length and engaging the interior threads of the body, and the plunger A, located in the body B, and having the packing b, said plunger extending beyond the body B, substantially as set forth.

CHAS. B. LOCKE.
